UNITED STATES PATENT OFFICE.

RICHARD WEBB BURNETT, OF MONTREAL, QUEBEC, CANADA.

VENTILATOR.

1,117,973.

Specification of Letters Patent. Patented Nov. 24, 1914.

Application filed August 25, 1911. Serial No. 646,008.

To all whom it may concern:

Be it known that I, RICHARD WEBB BURNETT, residing at the city of Montreal, Province of Quebec, Dominion of Canada, 5 have invented certain new and useful Improvements in Ventilators; and I do hereby declare that the following is a full, clear, and exact description thereof.

My invention relates to ventilators for 10 refrigerator cars, and more particularly to the ventilators of the type combined with the hatch through which the ice is loaded, but it is applicable to cars of all types.

The object of my invention is to provide 15 a ventilator within the height required for track clearance, and which will be cinder-proof, and simple and inexpensive to construct; and to this end the invention may be said briefly to consist of a three sided 20 rectangular rim or flange projecting above three sides of the hatch, the non-flanged side being toward the end of the car, and a cover hinged to the flange toward the middle of the car, and having side flanges over- 25 lapping the corresponding flanges of the rim. A sealing member and a ventilating member being both carried by the cover, and adapted to, at different times, close the open side of the rim.

30 For full comprehension, however, of my invention, reference must be had to the accompanying drawings, in which similar reference characters indicate the same parts, and wherein:

35 Figure 1 is a longitudinal sectional view of my improved combined ventilator and hatch arranged for ventilation; Fig. 2 is a similar view to Fig. 1, and illustrating the device closed; Fig. 3 is a part front elevation and part transverse vertical sectional view, drawn to a larger scale, of my improved combined ventilator and hatch arranged for ventilating; and Fig. 4 is a detail view illustrating the previous or venti- 40 lating member removed.

The car illustrated is an ordinary box car having hatches in its roof for charging with ice and for use for ventilation when desired. One of the hatches is illustrated 50 at 2 and it is provided with four inclosing wooden walls 3. For the purpose of my invention I cut down the wall nearest the end of the car. Three sides of this hatch wall are inclosed by a steel plate bent to present three 55 flanges 5, 6 and 7, and end abutment flanges or jambs 8 overlapping the ends of the

fourth side, such plate being flanged at its lower edge as at 10, and fastened thereby to the car roof. This plate constitutes the base of my appliance. The cover also consists of sheet steel, and has a top 15 and tapered side flanges 16 reinforced by ribs 17, the smaller end of the tapered sides being toward the middle of the car and attached by a hinge to the car roof. This end has a shallow flange 20 adapted to register with the corresponding flange of the base, and the opposite ends of the side flanges are bent inwardly to form abutment flanges or jambs 21 similar to the abutment flanges or jambs 8 of the base. A closure flange or door 23 adapted to fit tightly against the jambs 21, is hinged to the free edge of the cover, and seals the cover when shut down. A hasp 25 serves to lock the cover down and the sealing door in effective position, as shown at the left in Fig. 1. A ventilator door is also hinged to the free edge of the cover just inside of the sealing door, and it is adapted to fit against and inside of the jambs 8 of the base, and rest upon the roof, and a hasp 30 affords means for locking this door and the cover in ventilating position, as shown at the left in Fig. 1 and turned up with the screen in Fig. 2.

The ventilating sections or members heretofore used were defective in that they failed to keep out the fine cinder particles, and I have solved this problem by making my ventilator member of an oblong rectangular frame 35, having wire netting of comparatively coarse mesh secured as at 36 and 37 to the opposite sides thereof, the outer sheet 36 being of less depth than the inner which inner sheet extends completely across the frame thus protecting the entire opening therethrough; the purpose being to provide a space along the lower edge of the outer netting to permit cinders and other dirt which happens to pass through the outer netting and stopped by the inner netting to roll out onto the roof. And I have discovered that with spaced sheets of netting, a coarse mesh may be used even more effectively, in so far as keeping out the smaller foreign particles is concerned, than finer material, for the reason that the outer sheet breaks their force and those that pass are falling when they strike the inner sheet, and consequently do not pass it.

In Fig. 2 my combined ventilator and hatch seal is shown fastened in position seal-

ing the hatch as when ventilation is not required, and in Fig. 1 the appliance is shown with the screen set for ventilating, and the sheet metal door 23 thrown back in full lines 5 and dotted in position acting as a valve reducing the ventilation area my improved appliance being shown in Fig. 3 arranged for ventilation to its full capacity the sheet metal door being thrown back and resting 10 on the top of the cover.

This combination ventilator and hatch cover is of minimum height as either a sealing cover or ventilator, and effective for either use. The cover is hinged in place, and 15 the entrance of sparks at the hinged end when sealed or used, for ventilation, is prevented by taking up the slack necessary between the hinged end of the cover and the base or mouth of the hatch, to enable the 20 cover to be set in different angular positions. This is done by a curved plate 50 attached permanently to the flange 6 and having sufficient spring to follow the cover to its full ventilating position thus embracing 25 the hinge and constituting a spark arresting seal at this point. The plate is preferably as before mentioned fastened directly to the flange 6 of the base, and a series of hinge knuckles 51 are mounted thereon, the 30 other hinge knuckles 52 being formed on the flange 20 of the cover and they are supplemented by lugs 53 while the whole of the hinge structure is braced by a pair of relatively heavy lugs 54 fastened to the roof of the 35 car.

The curved plate 50 fits snugly at its side edges against the interior of the side edges of the cover with its free edge abutting against the inside of the flange 20; and when 40 the cover is moved to different ventilating positions, the natural resiliency of the plate causes it to follow the flange 20 and keep in bearing relation therewith, thus preventing the entry of sparks or other particles.

45 In order to use the hatch for a ventilator the cover is lifted sufficiently to allow the screen to drop to the position shown in Fig. 1, and the pin 300 is drawn out; and when it is desired to close the cover down tightly 50 it is lifted the screen swung back to the position shown in Fig. 2 and the pin 300 is again inserted thus holding it in position.

Although I have illustrated and described the cover, which is the principal feature of 55 my invention, attached to a metallic base distinct from the mouth of the hatch, such cover may be made to co-act directly with the mouth of the hatch if the latter is of suitable construction; and the particular construction of screen with spaced sheets of 60 screening material may be applied to other ventilating uses without departing from the spirit of my invention. Furthermore the spark and dust arresting plate 50 may be 65 used in connection with any car door where

leakage is likely to occur, within the scope of my invention.

What I claim is as follows:—

1. In a car the combination with an ice loading hatch, of a combined sealing and 70 ventilating member consisting of a cover having an impervious door and a screen both secured to the free edge of the cover, the impervious door being constructed to individually support the cover in sealing position, and the screen being constructed to individually support the cover in ventilating position.

2. In a car the combination with a hatch, flanges encircling all sides of the hatch excepting one side, of a cover hinged adjacent to the flange opposite the non-flanged side and having flanges for engagement with the side flanges of the hatch, and an impervious door and a screen door both hinged to the 80 cover at the free edge thereof, and each adapted to extend across the said non-flanged side of the hatch, the impervious door being constructed to support the cover in sealing position and the screen door being constructed to support the cover in ventilating position.

3. In a refrigerator car the combination with the roof of a combination hatch cover and ventilator consisting of the hatch having vertical flanges at three sides and one side non-flanged, a cover for the hatch hinged adjacent to the side thereof opposite to the non-flanged side, an impervious door hinged to the cover at the free edge thereof 95 and approximately equal in length to the non-flanged side of the hatch, a screen secured to the free edge of the cover inside of the impervious door, means for locking impervious door in position closing the said non-flanged side of the hatch, and means for locking the said screen door across the said non-flanged side of the hatch.

4. In a refrigerator car the combination with the roof of a combination hatch cover and ventilator consisting of the hatch having vertical flanges at three sides and one side non-flanged, a cover for the hatch hinged adjacent to the side thereof opposite to the non-flanged side, an impervious door hinged 110 to the cover at the free edge thereof and approximately equal in depth to the flanges of the hatch, a screen also hinged to the free edge of the cover inside of the impervious door, means for locking the impervious door in position closing the non-flanged side of the hatch, and means for locking the said screen door across the said non-flanged side of the hatch.

5. In a refrigerator a combination hatch 125 cover and ventilator consisting of a base having three closed sides and one open side, a cover for the base hinged and adjacent to the side thereof opposite to the open side, an impervious door hinged to the free edge 130

of the cover and approximately equal in depth to the base, a screen door also hinged to the free edge of the cover inside of the impervious door, means for locking the impervious door in position closing the open side of the frame, means attaching the free edge of the screen door to the cover, means for locking the said screen door across the said open side of the base, and a resilient

5 plate fastened to the base and between the

10

said base and the cover and arresting any sparks which might pass through the hinge.

In testimony whereof I have signed my name to this specification in the presence of two witnesses.

RICHARD WEBB BURNETT.
